HAROLD F. SHAW, OF LEOMINSTER, MASSACHUSETTS, ASSIGNOR TO F. A. WHITNEY CARRIAGE COMPANY, OF LEOMINSTER, MASSACHUSETTS, A CORPORATION OF MASSACHUSETTS

CLOTHES HAMPER

Application filed October 31, 1929. Serial No. 403,773.

This invention relates to portable receptacles from which the accumulated contents are emptied from time to time. The object is to provide a construction for such a container facilitating such emptying.

My invention will be well understood by reference to the following description taken in connection with the accompanying drawings, wherein by way of example I have shown a clothes hamper, the construction of which is illustrative of the principles of my invention. In these drawings:

Fig. 1 is a broken section through the hamper on the line 1—1 of Fig. 3;

Fig. 2 is a similar view on a different scale showing the hamper being emptied; and

Fig. 3 is a section on the line 3—3 of Fig. 1, but on a different scale.

Referring to the drawings, the hamper I have therein shown as an example of the invention is of wicker construction and embodies a top frame 5, over which closes a hinged lid 7 and through which the soiled garments are deposited, and a bottom frame 9, which two frames may be spaced by the vertical frame members 11 at the corners, the sides of the hamper being formed by the wicker fabric 12 attached over the framework thus provided. To provide hand grips by which the hamper may be lifted I may form openings 13 through the fabric at either side to permit the fingers of the hand to be inserted to underlie the side elements of the top frame 5 for lifting the hamper. The margins of the fabric around the opening may be secured to the U-shaped auxiliary member 15 attached to the lower face of the corresponding side element.

The central opening defined by the bottom frame 9 herein forms a discharge opening for the contents of the hamper which is normally closed by a closure 17 hinged at 19 to swing outwardly and downwardly, as illustrated in Fig. 2. This closure may normally be held in closed position by means of

latches 21 which may be pivoted to the side elements of the bottom frame 9 and have suitable bills engaging keepers or strike plates 23 on the ends of the closure. To project the latches so that they will snap into engagement with the keepers I may utilize rods

25 pivoted to the tails of the latches and having their upper ends guided in the members 15 and springs 27 surrounding the rods and interposed between such members and abutments 29 carried on the rods, the springs tending to rock the latches 21 to the position shown in Fig. 1. Thus if the bottom is depending in the position shown in Fig. 2, the mere operation of setting the hamper down upon the floor will cause the closure to shut and be latched.

I provide means whereby the bottom closure 17 may be conveniently released for discharging by gravity the contents of the container when the latter is lifted by the hand grips, preferably substantially as a part of the same act. Herein I have shown the rods 27 as extending into the hand-receiving openings and being provided with heads 31 disposed in said openings. One or more fingers of the hand introduced into the opening may grasp the head and as the hamper is lifted a natural gripping movement of the fingers will lift rods 25, retract the latches 21 against the force of springs 27 and permit the bottom to swing under gravity to the position of Fig. 2 so that the clothing may be discharged through the then unobstructed bottom opening. When empty the mere act of setting the hamper down will again close the bottom. The hamper may be freely moved by means of the hand grips without spilling the contents provided the heads 31 are not pressed on at the same time.

I prefer to form the bottom closure 17 in a single piece as shown and to hinge the same on the same side of the hamper as the cover 7. This is because such a hamper is usually placed against a wall and the cover lifted

from in front to permit articles to be placed therein. In emptying it the user naturally stands in front, at the right in Fig. 2, and lifts the hamper as illustrated in Fig. 2, raising the further bottom edge higher than the high bottom edge. If the closure is pivoted on this further bottom edge, it swings open and may clear the floor without requiring that the hamper be lifted very high.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

Claims:

1. A clothes hamper having a discharge opening at the bottom thereof, a hinged closure therefor, latching means for the closure, hand grips at the top of the hamper, and means for releasing the latching means having an operating portion disposed adjacent a hand grip to be within reach of a portion of the hand engaging the grip thus providing for manipulation thereof while said hamper is supported thereby.

2. A clothes hamper having a discharge opening at the bottom thereof, a hinged closure therefor, latching means for the closure, hand grips at the top of the hamper constructed to receive an underriding support from the fingers, and means for releasing the latching means comprising a retractable member having a head presented adjacent a hand grip to be engaged for lifting by one or more of the fingers which are presented to the grip.

3. A portable receptacle having an opening at the top to provide for placing articles therein and having a hinged bottom adapted when released to swing downwardly from the receptacle, latch means for engaging and holding said bottom in position when the receptacle is set down, handle means providing for bodily lifting said receptacle and latch releasing means disposed for actuation by the person lifting the receptacle while he supports the same by said handle means.

4. A portable receptacle comprising a top frame, a bottom frame, a covering forming the sides of the container and having openings beneath said top frame to receive the hands to grasp the frame, a bottom hinged to the bottom frame, latches pivoted in the bottom frame to engage and hold closed the bottom, guide elements adjacent the bottoms of said opening, and rods extending from said latches through said elements having heads exposed in the openings.

5. A portable receptacle of the type providing for the gradual accumulation of contents therein having a deposit opening in its

upper portion, hand grips at opposite sides and near the top providing for lifting the receptacle, an opening near the bottom for gravity discharge of the contents there-through, a closure for said opening, and means controlling the opening of said closure comprising an actuating part adjacent a hand grip for actuation by the hand engaged therewith.

In testimony whereof, I have signed my name to this specification.
